(57) **CLAIM**

The ornamental design for a couch cover, as shown and described.

DESCRIPTION

FIG. 1 is a perspective view of a couch cover showing my new design.

FIG. 2 is a front view of the embodiment shown in FIG. 1.

FIG. 3 is a rear view of the embodiment shown in FIG. 1.

FIG. 4 is a left side view of the embodiment shown in FIG. 1.

FIG. 5 is a top view of the embodiment shown in FIG. 1.

FIG. 6 is a bottom view of the embodiment shown in FIG. 1.

FIG. 7 is an alternative perspective view of the embodiment shown in FIG. 1.

FIG. 8 is a top view of the embodiment shown in FIG. 1, showing the embodiment of FIG. 1 in an open position.

FIG. 9 is a perspective view of a second embodiment of a couch cover showing my new design.

FIG. 10 is a front view of the embodiment shown in FIG. 9.

FIG. 11 is a rear view of the embodiment shown in FIG. 9.

FIG. 12 is a left side view of the embodiment shown in FIG. 9.

FIG. 13 is a top view of the embodiment shown in FIG. 9.

FIG. 14 is a bottom view of the embodiment shown in FIG. 9.

FIG. 15 is an alternative perspective view of the embodiment shown in FIG. 9; and,

FIG. 16 is a top view of the embodiment shown in FIG. 9, showing the embodiment of FIG. 9 in an open position.

The broken lines in the drawings represent portions of the couch cover that form no part of the claimed design. The broken lines in FIGS. 7 and 15 represent environment and form no part of the claimed design.

The stippling shown illustrates contour shading of the couch cover.

1 Claim, 12 Drawing Sheets
